D. W. MEANS
VALVE GRINDING TOOL

Filed May 17, 1924

FIG. 1

FIG. 4

FIG. 3

Delbert W. Means

U. S. Charles

Attorney

UNITED STATES PATENT OFFICE.

DELBERT W. MEANS, OF WICHITA, KANSAS.

VALVE-GRINDING TOOL.

Application filed May 17, 1924. Serial No. 714,091.

To all whom it may concern:

Be it known that I, DELBERT W. MEANS, a citizen of the United States, residing in Wichita, county of Sedgwick, and State of Kansas, have invented new and useful Improvements in Valve-Grinding Tools, reference being had to the accompanying drawings, which form a part of this application.

My invention relates to a valve grinding tool.

The object of my invention is to provide a tool that is small, so that it may be carried in an ordinary tool chest and also to have a tool that is simple in construction, and providing few parts.

A still further object of my invention is to provide a tool, that when it is being operated it has the possibilities of varying the tension while grinding.

Referring to the drawings, Fig. 1 is a side view, showing the tool in its operative position on a valve, such as is used in an internal combustion gas engine.

Fig. 2 is a transverse section, taken on line A, looking in the direction of arrow.

Fig. 3 is a longitudinal section, taken on line B of Fig. 2, looking in the direction of arrow.

Fig. 4 is a detailed sectional view, taken on line C, looking in the direction of arrow.

1 is a square shaft twisted spirally, having a spur member 2, pivotally connected to one end, said member having spurs adapted to seat in perforations on the face of the valve

3. On the opposite end of said shaft is a handle 4, which is revolvably mounted thereon. 5 is a grip, constructed preferably as follows: Said grip has a shell 6, a sleeve 7 mounted thereon, and the sleeve has an integral head 8. 9 is a plate having a rectangular opening 10, adapted to receive two rollers 11, each of which has its face angularly grooved so that the rollers will fit snugly over the shaft, said rollers being set directly opposite each other. Said rollers are pivoted between said plate and the head of the sleeve, and the plate is firmly attached to the head by screws 12; also to the shell 6 by means of screws 13.

When being used, the grip 5 is reciprocated upon the shaft and held firmly to prevent the grip from rotating; thus the shaft will be rotated alternately in opposite directions. Suitable pressure downward upon

the tool is maintained by one hand bearing 55 down upon the handle 4.

The rollers function as very efficient anti-friction elements, and the sleeve 7 functions as a protecting means to prevent the shaft from wearing out the square opening in the 60 grip.

I do not confine myself to any certain material for the shell, as it may be made of wood, hard rubber, or metal. Neither do I confine myself to the exact shape of the grip 65 as it may have a rough surface or polygonal in shape. The principle is that of holding it firmly, causing the spiral to rotate as the valve is being ground, therefore the manufacturer may deviate from the exact shape 70 and size shown.

To grind a valve, the usual grinding paste is applied to the seat of the valve, and the valve being placed in position, I place the spur member of my grinding tool in apertures in the valve that is provided for grinding purposes, and the spur member being pivotally mounted to the spiral shaft will accommodate itself though the shaft is held slightly out of alignment, and then by forcing the grip from end to end the valve is caused to rotate, reversing the revolutions as the grip travels to and fro on the shaft. The reversed motion has a tendency to reduce or increase the tension, allowing the 85 paste to distribute over the face of the valve and valve seat.

Such modifications may be made, as fall within the scope of the appended claim, and having thus described my invention, what I 90 claim as new and desire to secure by Letters Patent is;

In a valve grinding tool, a spiral shaft, means for connecting said shaft to the valve, and means for holding said shaft in alignment with the shaft of said valve, an actuating grip slidably mounted on said shaft, said grip comprising a shell, having a sleeve, in the center thereof and the said sleeve having a bearing on one end thereof, sheaves 100 mounted in said bearing, a plate registering with said bearings and sheaves and functioning as a cap for said bearings, means for firmly attaching said plate to said bearings, said plate functioning as means for binding 105 said sleeve and bearings to the said shell for the purpose set forth and described.

DELBERT W. MEANS.
